UNITED STATES PATENT OFFICE.

JOHN HEWITT, OF PITTSBURG, PENNSYLVANIA.

IMPROVEMENT IN SAD-IRONS.

Specification forming part of Letters Patent No. 137,201, dated March 25, 1873.

To all whom it may concern:

Be it known that I, JOHN HEWITT, of Pittsburgh, in the county of Allegheny and the State of Pennsylvania, have invented certain new and useful Improvements in Sad-Irons, of which the following is a full, clear, and exact description, reference being had to the accompanying drawing and the letters of reference marked thereon making part of this specification, in which—

Figure 1 is a side view, one side of the ironing-plate being down. Fig. 2 is a side view, the reverse or polishing-face being down.

The object of my invention is to provide a reversible combined sad and polishing iron, and one in which the polishing-face shall be at or near the center, and which permits, in ironing, the gloss to be imparted to the shirt-bosoms, &c., with the iron held in a natural position, and without tilting it so as to act on its toe or heel, as in other devices of this character, and in which position a moment's reflection will convince any one the iron is difficult to hold, and consequently difficult to use. The nature of my invention consists in forming the block or plate with one face flat, and to be finished as a sad-iron, and the other or reverse face tapering from a point at or near the center so as to leave a polishing friction-ridge at this section, and which extends entirely across the plate. When the iron is formed with its reverse face angular or tapering in both directions, or toward the toe and heel, the polishing-ridge is afforded. When the iron is held in a perfectly true position, and when the angular taper extends from the center so as to furnish only one inclined section, the polishing-ridge is afforded simply by giving a slight forward inclination to the toe of the iron. The weight of the plate may be so distributed that when the polishing-face is turned down the heft of the iron shall cause it to fall on its inclined face.

The construction and operation of my invention are as follows: A is a reversible sad-iron block or plate, and B is the handle, and its shanks *b b* are so secured to the plate A at pivot-centers *a a* as to allow of the free revolution of the plate between the shanks. C is a spring-latch or other fastening, and these are all constructed in the usual manner, and so arranged that while the latch holds the block in a fixed and steady position when in use, at the same time permits of the plate A

being reversed at pleasure and of the operator working with either face desired. One face, D, of the plate A is flat, and is finished to be used as a sad-iron, and the other face, D', is inclined or tapering, extending in an angular direction from a point at or near the center toward the toe, and is to be finished as a polishing-iron, the center ridge *d* being used for that purpose; and by a rapid movement of this ridge *d* over a shirt bosom or other like surface the desired gloss is imparted.

Instead of the weight of metal being distributed so as to leave the greatest weight of metal in the heel section of the iron, as in Fig. 1, it may be so distributed as to leave the greatest weight at the opposite direction, so that the tendency of the iron shall be, through its own heft, to fall and rest on its inclined face. In either case, by the slightest inclination of the handle the iron is so held as to leave only its polishing-ridge *d* in contact with the garment it is desired to iron.

From the foregoing description the operation of the iron will be readily understood. The face D is turned down and held in position by the spring-latch to be used as a smoothing-iron. When the operator has finished this work of the sad-iron and desires to use the polishing-face he simply has to undo the latch and reverse the plate A and again let the latch automatically fasten it; and when, as has been said, by the slightest inclination of the handle in the hand and by a movement entirely similar to that of the sad-iron, the ridge *d* is in position to impart the desired gloss or polish.

What I claim as new, and desire to secure by Letters Patent of the United States, is—

The reversible plate A having one face, D, flat and finished as a sad-iron, and the other face, D', tapering from a point at or near its center so as to leave a polishing-ridge, *d*, extending entirely across the plate and about midway thereof, substantially as described, as and for the purpose specified.

In testimony whereof I have signed my name to this specification in the presence of two subscribing witnesses.

Witnesses: JOHN HEWITT.

JOS. T. K. PLANT,
EDWIN JAMES.
